PRECAST SLAB AND BUILDING
CONSTRUCTION

Clarke F. Davis, Short Hills, N. J., assignor to
American Cyanamid & Chemical Corporation,
New York, N. Y., a corporation of Delaware

Application July 9, 1935, Serial No. 30,432

4 Claims. (Cl. 72—40)

The present application is directed to a part of the subject matter shown and described in my co-pending application Serial No. 655,591, filed February 7th, 1933.

5 The present invention relates to a building construction of precast units where those units are provided with metal on their abutting edges, said metal being so arranged as to interlock the edges together, such as by tongues and grooves.

10 The invention is also directed to the units per se. The principal object of the invention is to provide a construction of the above type which is particularly adaptable for floors, roofs, walls, ceilings or combinations thereof.

15 To this end, the invention contemplates a precast unit of set cementitious material of which gypsum is typical, either with or without fillers such as wood chips and with or without internal reinforcing. This unit is provided on two adjacent faces with a sheet metal covering, the ends 20 of which are embedded in the body material, the metal covering being tongued and grooved. This particular unit may serve as a corner post between two vertical walls, a sill between a floor 25 and a wall, a sill between a wall and a ceiling, a sill between a wall and a roof or a roof ridgepole.

Other elongated slab units also of set cementitious material, such as gypsum, may be used as 30 the elements from which the walls, floors, ceilings or roof are constructed, and are provided on their longitudinal edges with metal elements having complementary tongues and grooves. These several units are designed to be arranged 35 edge to edge with the metal portions in contact or partially in contact with the tongue of one engaging the other in an interlocking manner, the end unit likewise interlocking with the post or sill unit.

40 The invention further contemplates the offsetting of a portion of the metal edging from the main plane of the edge of a unit for a purpose more fully hereinafter described.

The invention further consists in the novel arrangement and construction of parts more fully hereinafter described and shown in the accompanying drawing, in which—

Fig. 1 is a sectional view illustrating the present invention;

50 Fig. 2 is a view along the line 2—2 of Fig. 1;

Fig. 3 is a perspective view of one embodiment of the invention.

Referring now with particularity to the embodiments illustrated, there is shown in Fig. 1 55 typical precast slabs A and B of a series, with

an intermediate joining unit C. In the view referred to and considering it from the standpoint of being a sectional plan view of a corner post and two abutting walls, the post C is substantially rectangular in lateral cross-section and 5 elongated to the desired extent. A sheet metal covering 1 is applied thereto and that portion on two adjacent faces thereof is provided with a tongue 2 and a groove 3. The ends 4 of the metal member 1 are embedded in the body of the unit C. 10 Each of slabs A and B may be cast of gypsum or the like, the edges thereof being provided with metal elements 5, the elements on opposite edges being correspondingly tongued and grooved. Likewise, the metal members 5 have their ends 6 15 embedded in the slab body. As shown, the slabs A and B may be longitudinally grooved or bisquettued on one face to permit of a slab of increased depth without corresponding increase in weight, although this bisquetting is not necessary. 20

Considering Fig. 1 from the above viewpoint, the unit C may be a corner post extending vertically between two vertical walls in which the slabs A and B are the end units. These slabs each engage the corner post C in an interlocking manner due to the provision of corresponding metal edge members. Obviously any number of units 25 A and B may be used, dependent upon the extent of the wall itself.

It will, of course, be obvious that a substantially close fit is desired between the tongues and grooves of the various interlocking units. It sometimes happens during manufacture that a part of the plastic material of which these slabs are made slips over onto the metal edge and 30 hardens there. This would normally cause an undesirable misfit of the units. In order to avoid this, one section 7 of the metal edge 5 may be offset from the plane of the unit edge so that as long as the part 5 fits closely with the neighboring portion of the metal element 1, a proper 35 tongued and grooved fit is assured. While, of course, this is not as desirable as the joint at the right hand end of Fig. 1, yet it does provide means whereby the danger of undue spacing 40 apart of the joint is materially lessened.

It will also be apparent that this same principle is applicable to a floor and wall where the member C acts as a sill. By turning Fig. 1 upside down, it will be noted that slab A then becomes part of a floor system, slab C the horizontal sill and slab B the first unit of those constituting a wall system. Obviously any type of finish may be applied to the floor and wall slabs A and B where desired.

Another aspect of Fig. 1 is that wherein it appears as a sectional view through the corner of a vertical wall and horizontal floor and/or ceiling. That is, slab B may be the top unit of a vertical wall, slab C the sill at the top of the wall and slab A the first unit of a ceiling and/or floor.

5 Still another aspect of Fig. 1 may be that of a sectional view of a roof. This may be observed by rotating Fig. 1 at an angle of 45° in a 10 clockwise direction. Slab C then becomes the ridgepole of a roof and slabs A and B the top 15 row of roof units.

In all of the above situations there is the same type of interlocking action secured, reinforced by the metal edging.

In the claims, where the word "surface" is used, it is intended to cover floors, roofs, ceilings, or walls or an appropriate combination thereof.

I claim:

20 1. A precast slab of set cementitious material having two adjacent faces covered by a metallic member, the edges of which are turned back into

the slab body, said slab having a tongue on one face and a corresponding groove on its adjacent face.

2. A precast slab of set cementitious material having two adjacent faces covered by metal, one 5 of said faces being tongued and the other correspondingly grooved.

3. A building construction comprising two surfaces at an angle to each other, each comprising interlocked precast units and a precast member interlocked between end units of said surfaces in which the abutting edges of the units and the precast member are faced with metal.

4. A building construction including two precast slabs with two edges adjacent, each of which 10 carries a metal facing member, the two members being tongued and grooved together, said members having areas in contact with each other, and other areas parallel to the first mentioned area but offset therefrom.
